3 Claims. (Cl. 61—45)

The invention relates to a walking support method for face workings, rearward and forward roof supports guided on one another being advanced alternately.

The present invention provides a method of this kind which can be used with frictional and hydraulic props and also with roof bars of conventional construction, and the method differs from the known comparable walking support method for roofs particularly in that the walking operation is effected without any interruption to the continuous support of the roof during any stage whatever. This means that unlike conventional methods in which the roof supports—props or frames—disposed successively in the strike are alternately released and then have to be re-locked after advance—with a very unfavourable stress on the roof—the latter is protected, i.e., remains at rest practically until it is supported on the gob side in accordance with the program after a corresponding advance in working.

The method according to the invention consists basically in that the forward and the rear roof supports are each formed from two units, which are disposed successively in the strike, and which are combined into groups, and which each consist of a prop and a roof bar, the said units being disposed immediately side by side and staggered with respect to one another by the length of a unit at the maximum, and the forward unit of the rear group is released and moved out of this initial position while being guided along the successive units of the forward group, as far as possible so as to directly follow the advance of the coal face, so as to be brought into a position projecting beyond the forward unit of the forward group and then, after respective re-locking and release is intermittently advanced further into the position adjacent the coal face until the rear end of its roof bar has reached the forward end zone of the roof bar of the forward unit of the initially forward group, whereupon the rear unit of the originally rear group is guided along the other group units which still remain locked, until it is drawn along to bring it up to the forward unit. The two units of the originally rear and now forward group then form the guide for the advance of the units of the other group in the same rhythm. Thus in each stage of the advance, there is an uninterrupted support for the roof which consists of at least three units following one another in the direction of the strike, these units remaining locked until the final phase of the advance.

The foremost unit may in the extreme case be in its position adjacent the coal face in a position in which the rear edge of its roof bar is flush with the forward edge of the forward bar of the adjacent unit. As a rule, however, there will be a certain degree of overlapping so that the guidance of the adjacent units on one another is not lost.

A particular advantage of the new method is that the elements of the units used with this method, namely props and roof bars, are of conventional construction, the only need for adaptation to the new method being that the roof bars of the adjacent groups are provided with inter-engaging guide means, for example rails or the like, at their mutually facing sides.

The roof bars of the units are preferably so underpinned as to load the head of the roof bar towards the coal face. This improves the conditions for guidance along the adjacent roof bar. The props of the individual sets are of course provided with base plates or skids enabling them to slide over the floor in the usual way.

The double-acting intermittently extensible advancing cylinders are required in principle for the advance of the individual groups with the above-indicated rhythm, 5 one such cylinder being provided for each of the two groups and acting on one unit of the group. In development of the invention, a single advancing cylinder may be provided which, after the completion of the advance of one group, performs the complete task, for example by means of a cross-head provided on its piston rod and to which the unit of the other group to be advanced is connected.

It will be apparent that the steps by which the elements are advanced in the various stages can be chosen to 20 have any desired values, so that the new method is equally advantageously suitable for stripping and for coal-getting methods in which a wide exposed roof area is to be supported as quickly as possible.

Moreover, the various steps in the advance need not be 25 performed for the full length in one operation, but may be divided up into a number of shorter steps following one another at intervals. This particularly has the advantage that there is then no need to use an advancing system having a very long extended length, but normal advancing cylinders of an extended length of 15 mm. may be used for the purpose. Other objects and advantages of the invention will become apparent from reading the 30 following detailed description of the invention when considered in the light of the accompanying drawings in which:

FIGURE 1 is a diagrammatic illustration, in plan view, 35 of a mine supporting assembly comprised of three sets, each of which consists of two groups of supporting elements which are arranged in side-by-side relationship in a typically supporting position;

FIGURES 2 to 5 show the apparatus illustrated in FIGURE 1 wherein the forward support units of one group of supporting elements on the left hand side of the drawing are actuated through varying advancing positions within the mine chamber to be supported;

FIGURE 6 shows apparatus illustrated in FIGURE 1 wherein the rear units of the group on the left hand side of the drawings are advanced up to the forward unit of the group; and

FIGURE 7 is similar to FIGURES 1 to 6 and shows the units of the groups on the right hand side of the drawing being actuated to different positions of support.

The accompanying drawings diagrammatically illustrate in plan view the consecutive stages of advance with the new method. Each of the two adjacent groups of roof supports consists of two units 1, 2 and 3, 4 respectively and each of the units consists of a roof bar borne by a prop indicated just by a dot in the diagrammatic illustration.

The drawing shows in each case three sets, each of which consists of two groups and which are arranged side by side at falling intervals, and the units of which, as illustrated, can be advanced either simultaneously or individually by means of the advancer devices (not shown)—advancer cylinders or mechanical devices having a similar action.

It will be seen that in the starting stage, as illustrated in FIGURE 1, the two units 1 and 2 of the rear group are so disposed with respect to the units of the forward group 3 and 4 as to be in a position in which the forward unit 1 of the rear group fully overlaps the rear unit 3 of the forward group. This position is not ab-

solutely essential, however, and has been chosen only to simplify matters.

In the next stage, the forward unit 1 of the rear group is guided along the units 3 and 4 of the forward group until it initially reaches a position, as illustrated in FIGURE 2, on the coal-face side of the forward unit of the forward group, in which position it secures the exposed roof area. FIGURES 3 and 4 illustrate the next stages, in which the forward unit has been advanced additionally until in the extreme case the stage illustrated in FIGURE 5 is reached. It should, however, be pointed out that the end stages which are shown in the purely diagrammatic drawing and in which there is no overlapping of the adjacent units of the forward and rear groups, has been chosen only to facilitate matters. In practice, there will always be a certain amount of overlapping and hence guidance of the adjacent units with respect to one another.

In the positions illustrated in FIGURES 4 and 5, respectively, the rear unit of the originally rear group is brought up into the position illustrated in FIGURE 6, from which the advance of the initially forward and now rearward group into the position illustrated in FIGURE 7, etc., takes place in the same way as described previously.

It will be clear from the drawing that in each stage the roof is continuously supported, even during the advance operation, namely by the units 2, 3, 4, in the stages illustrated in FIGURES 1 to 5 and by the units 3, 4, 1 and 3, 2, 1, etc., in the stage illustrated in FIGURE 6, and the roof is also supported during the advance of a unit, in the immediate vicinity of such unit, so that the roof cannot be disturbed by the release of the advanced unit.

Since, as already stated, the new method can be performed with conventional props and roof bars, a pit can at all times be changed over to the new method while continuing to use existing support material and utilise the advantages of the new method without expensive investment.

We claim:

1. A walking support method for mine roofs, first and second roof support groups being laterally disposed and guided on one another and advanced alternately, characterized in that said first and second roof groups are each formed of at least two units disposed successively along the mine roof, each of said units comprising an elongated roof bar and prop means therefor, said successive units being capable of abutting one another and also

capable of being spaced in relation to one another by the length of two units at the maximum, wherein the forward units of said first group is intermittently guided along said second group of units which remain in an unchanged position following the same along the mine roof so as to be brought into a position projecting as far as possible from the forward units of said second group so as to directly follow the advance of the coal face until its rear end reaches the zone of the forward end of the front unit of said second group, whereupon the rear unit of said first group is then guided along the units of said second group until the rear unit of said first group is advanced up to the forward unit of said first group, and thereafter the two units of said first group remain in an unchanged position and form the guide for the advance of the units of said second group in the same rhythm, in such a manner that in each stage of the advance the mine roof is supported continuously.

2. A method according to claim 1, wherein each of said units consists of a roof bar supported by a prop, said roof bars of said units of one of said groups being positively guided along said adjacent roof bar of the other group and being supported by its respective prop in such manner as to continuously support the mine roof.

3. A method according to claim 2, wherein the advances of each of said units is divided up into a plurality of relatively short advances following one another at intervals.
